UNITED STATES PATENT OFFICE.

EDOUARD SEIGNOL, OF NEUILLY-SUR-SEINE, FRANCE.

WATCH.

1,413,941.

Specification of Letters Patent. Patented Apr. 25, 1922.

Application filed January 18, 1921. Serial No. 438,148.

To all whom it may concern:

Be it known that I, EDOUARD SEIGNOL, citizen of the French Republic, residing at Neuilly-sur-Seine, Department of the Seine, 5 in France, have invented certain new and useful Improvements in Watches; and I do hereby declare the following to be a full, clear, and exact description of the invention, such as will enable others skilled in the art 10 to which it appertains to make and use the same.

The mechanism of watches and horological movements is generally supported between superposed plates, connected together 15 by pillars which are supported at one end on one of the plates by a screwed or riveted head and are traversed at the opposite end by a pin. Braced or stayed sockets or collars are threaded on the pillars between the 20 plates, which sockets or collars serve to support the escapement. The plate-block thus formed does not permit of an exact centering of the plates and lacks rigidity; it is therefore unsuitable for precise production 25 en masse without retouching or finishing.

These inconveniences are avoided by the method of construction forming the subject matter of the present invention which ensures perfect centering of the plates as well 30 as exact marking or laying out of their relative positions.

The accompanying drawing shows by way of example a constructional form of the invention.

35 Figure 1 is a longitudinal section through the axis of the watch case.

Figure 2 is a plan of the mechanism.

The supporting frame-work of the watch mechanism is formed by a cylindrical casing 1, the outer or upright wall of which 40 may be completely closed or in the form of an openwork casing. An openwork casing, however, has the advantage of decreasing the weight of the whole arrangement and 45 facilitates mounting and inspection of the mechanism.

If for example there are three plates, the casing is bored internally to three different diameters and the plates 2, 3 and 4 are themselves cut or worked to the corresponding 50 diameters. The lower plate 4 rests on the lugs or projections 5 of any suitable form and number and the plates 2 and 3 are supported on the projections or ridges formed

on the interior wall of the casing. In order 55 to ensure the proper support of the plates they may be applied or supported individually on the projections or ridges of the casing by means of pins having their upper faces flush with the plates or by means of 60 fixing screws.

The plates may as shown be provided with a number of holes suitably spaced apart and through which screwed pins 6 are passed so that the lower screwed ends thereof engage 65 in the lugs or projections 5 while the upper ends or heads of the pins bear on the upper face of the plate 2.

In order to obviate the individual fixing of each plate the maintenance of the plates 70 on the lugs or projections is ensured by helical springs 9 coiled on the screwed pins 6, the said springs being of suitable power and length and compressed by the screwed pins 6. The springs 9 coiled on the pins 6 could 75 be replaced by a single spring compressed between each pair of plates or by bow springs, or by any other suitable resilient means.

In order to avoid rotation of the plates 80 in the interior of the watch case and especially to permit of their position being marked off exactly, each plate is slotted on its periphery the said slots engaging keys 10 secured by any suitable means to the wall 85 of the casing. Each plate may be provided with one or more than one slot adapted to engage a key 10.

In the movements of watches or other horological mechanism which does not require 90 a very high finish the casing can be cast and in this case the locking key or the locking keys instead of being removable or attachable could be cast with the casing as a whole.

The construction and arrangement hereinbefore described allows of very fine adjustment of the plates in the interior of the casing and ensures great rigidity to the block of mechanism as a whole, even if there exists 100 a slight play of the screws 6 in the corresponding holes in the plates. Such is not the case of ordinary pillars as used in watch and clock construction which when not locked in position in the plates allow of relative movement between the said plates.

Claims.

1. A watch mechanism supporting frame-

work, comprising a casing formed with different internal diameters producing annular shoulders, discs or plates supported on said shoulders, and screws or pins to retain 5 said plates in position on said shoulders.

2. A watch mechanism supporting framework, comprising a casing formed with different internal diameters producing annular shoulders, discs or plates supported on said 10 shoulders, screws or pins passing downwardly through said plates to retain the same in position on said shoulders, and a key secured to the casing and engaging the edges of said disc to prevent any relative circumferential movement thereof. 15

3. A watch mechanism supporting framework, comprising a casing formed with different internal diameters producing annular shoulders, discs or plates supported on said shoulders, screws or pins passing downwardly through said plates resilient means 20 carried by said screws between said plates to retain the plates in position on said shoulders, and a key secured to the casing and engaging the edges of said discs to prevent any relative circumferential movement thereof. 25

In testimony whereof I affix my signature.

EDOUARD SEIGNOL.
